UNITED STATES PATENT OFFICE

VICTOR HENRI, OF ZURICH, SWITZERLAND, ANDRÉ HELBRONNER, OF PARIS, FRANCE,
AND MAX von RECKLINGHAUSEN, OF NEW YORK, N. Y.

APPARATUS FOR STERILIZING LIQUIDS BY MEANS OF ULTRA-VIOLET RAYS.

Original application filed October 31, 1910, Serial No. 589,995. Divided and this application filed April 2, 1918. Serial No. 226,346.

To all whom it may concern:

Be it known that we, VICTOR HENRI, a citizen of the Republic of France, and residing at Zurich, Switzerland, ANDRÉ HELBRONNER, a citizen of the Republic of France, and residing at Paris, France, and MAX von RECKLINGHAUSEN, a citizen of Germany, and residing at New York, in the county of New York and State of New York, have invented certain new and useful Improvements in Apparatus for Sterilizing Liquids by Means of Ultra-Violet Rays, of which the following is a specification.

This invention which constitutes the subject matter of this application, relates to the treatment and sterilization of liquids by means of ultra-violet rays. This application is a division of our copending application Serial No. 589995, filed October 31st, 1910, and inasmuch as the objects, purposes, and advantages of sterilization by means of ultra-violet rays have been elaborately discussed in that application we will proceed to a discussion, in specific terms, of the apparatus which we are specifically claiming herein.

This particular application has to do with apparatus for destroying bacteria in water supply systems by means of ultra-violet rays, and has for its object certain improvements in elements adapted to sterilize or destroy the pathogenic bacteria in a water supply system where the pressure may exceed that of the atmosphere.

The most convenient source of ultra-violet rays known at the present time is the mercury vapor lamp having a container of quartz, and a lamp of this character is therefore preferable for sterilization purposes. Considerable difficulty has, however, been experienced in operating such lamps in a gaseous environment where the pressure exceeds that of the atmosphere, because, in the first place, heated quartz is pervious to gases, and, secondly, it is difficult to seal the leading-in wires into the lamp in such a manner that the joint will hold good for any length of time. The object therefore of the present invention is to construct the apparatus in such a manner that the lamps operate either under ordinary atmospheric pressure or in a vacuum, so that there is no danger of gases penetrating into the interior of the lamp through its walls.

We therefore provide the apparatus, in accordance with this invention, with means for illuminating the liquid from the exterior through a wall which is wholly transparent to ultra-violet rays or transparent on the side which is located in the direct path of the said rays. 55

As ultra-violet rays penetrate more deeply into the water or other liquid to be sterilized they become less active and therefore the parts of the water nearest the source of 65 ultra-violet rays will be acted upon to a greater extent than those parts which are farther away. In order therefore to secure uniformity and a sufficiency of action on the total bulk of water treated, it is desirable 70 to provide means for circulating the water through the apparatus so that each and every molecule of the same are acted upon to the necessary extent, and as far as possible to an equal degree. For this reason 75 the water should be circulated and agitated within the sphere of action so that all particles of fluids will not only flow through that portion of the apparatus where they will receive the maximum effect of the rays 80 but also move about in such manner that said particles will receive the rays from all sides. To do this, in this particular case, guides or baffle plates are employed, care being taken, however, to so arrange the parts 85 that such guides or baffle plates do not shelter any parts of the water from the rays.

In the drawings:

Fig. 1 is a plan view partly sectional of a sterilizing chamber having a number of 90 tubular windows arranged in the form of a grille.

Fig. 2 is a perspective view of a modified form illustrating a number of sterilizing chambers or compartments each of which is 95 provided with a window permeable to the ultra-violet rays, said windows facing the part of the lamp which emits such rays.

Fig. 3 is a perspective view of a further modification having windows facing the 100 part of the lamp which emits the ultra-violet rays.

Fig. 4 illustrates the preferred construction of an artificial means for creating eddy currents in the water as it flows through 105 the apparatus.

Fig. 5 illustrates a modification of the apparatus shown in Fig. 4.

- Referring to the drawings in detail, and first to the construction shown in Fig. 1, we provide the apparatus with one or more tubular windows permeable to ultra-violet rays and the lamp capable of emitting such rays is supported in or near said windows so that the ultra-violet rays emitted by the lamp pass through the windows and act upon the liquid passing through the apparatus.
- 10 The tubular windows are provided with connecting passages and the apparatus arranged so that the liquid passes through the tubes, one or more lamps being located outside the tubes in proximity thereto. To this end a 15 number of quartz tubes 10, constituting chambers for the liquid to be sterilized, having any suitable shape are mounted with their open ends attached to the connecting passages 11, which may be made of metal 20 or other suitable material. The connecting passages 11 permit the water to pass from one quartz tube to the next in series. The lamp 12, provided if desired with a reflector 13, is supported adjacent the grille and 25 as the liquid passes through in the direction shown by the arrows, it is exposed to the ultra-violet rays emitted by the lamp, which pass through the windows. The grille is provided with an inlet 14 and an outlet 15 30 for the liquid to be sterilized.

In the modified form of apparatus illustrated in Figure 2 the small sterilizing element comprises two tubes or chambers 16 of substantially semi-circular cross section 35 through which the water to be sterilized is caused to pass in succession. The chambers are provided with any suitable interconnecting means 17. The chambers are so arranged that their flat sides face each other 40 with a space between them in which the lamp 12 is located. The flat sides are provided with quartz windows 18 so that the rays can pass through and act upon the water which is flowing through the same. Suitable 45 inlet and outlet pipes 19 and 20 are employed.

In the modified construction shown in Fig. 3 the lamp 12 is surrounded by a number of chambers 21, which are substantially trapezoidal in cross section and are connected together by the pipes 22 so that the water to be sterilized passes through them in succession. These chambers are provided with quartz windows 23 in those sides which are 50 nearest the lamp and the sloping or inclined sides of the chambers are arranged substantially in a radial direction from the lamp tube, thus not only avoiding shadows within the chambers but also efficiently utilizing 55 the maximum amount of rays. The water which passes through the chambers from the inlet 24 to the outlet 25 is throughout its course directly exposed to the ultra-violet rays emitted by the lamp and can thus be 60 efficiently sterilized. It will be obvious that

the number of chambers located around the lamp in this manner may be varied, since they may be arranged to surround it on all sides, or the lamp may be provided with a suitable reflector 26 on that side where no 70 chamber is provided as shown in broken lines.

As previously pointed out it is sometimes necessary, in order to economically and efficiently effect a thorough sterilization of the 75 liquid, to provide an artificial means for imparting a rotary motion to the liquid or for producing local eddy currents therein. To this end, and in order to agitate and circulate the liquid so that particles of solid 80 matter in the same are turned over and over, and in order to bring the water which is passing under one lamp near the bottom of the apparatus, so that when it passes under the next lamp it is brought nearer the 85 top, baffle plates are arranged as shown at 27, Fig. 4. These baffle plates are preferably made of metal and are so constructed that the liquid passing through apertures in the same has a rotary or swirling motion 90 imparted to it. A simple method of accomplishing this object is illustrated by Figs. 1 and 4. Two cuts at an angle are made in the plate 27 and the material between the cuts is bent out in the direction of the flow 95 of the liquid, so that the outstanding triangular portion forms a lip 28 which deflects the liquid passing through the aperture 29 and, impinging thereon, forms eddy currents and cause the current of liquid to take 100 up a rotary or swirling movement. Any convenient number of these apertures with the corresponding lips may be provided in each baffle plate according to the dimensions 105 of the trough and the rate at which the water flows through the same.

In the form of construction shown in Fig. 1 the baffle plates are located in the passages of the conduit about midway between two successive sources of ultra-violet rays. Thus the water has sufficient time, after being stirred up on passing the baffles 27, to settle down again before it again comes underneath the succeeding rays.

The modified form of circulating baffle 115 shown in Fig. 5 is provided with tubular passages 30 which are arranged to lead the water from the top of the conduit to the bottom and vice versa. In connection with Figs. 2 and 3 it will be understood that the interconnecting tubes 17 and 22 may be provided with baffle means similar to the baffle 120 illustrated in Fig. 1.

Although the apparatus is particularly intended for destroying bacteria in a water supply system where the pressure exceeds that of the atmosphere it is also suitable for treating water by means of ultra-violet rays at ordinary atmospheric pressure, and we find furthermore that it may be advanta- 125 geous to use the apparatus in this manner.

geously employed for treating with ultra-violet rays liquids which are somewhat less translucent than water, such as white wines for the purpose of aging them and for carrying out various chemical reactions in liquids by means of the ultra-violet rays.

It is to be understood that we do not limit ourselves to the precise constructions and arrangements shown and described as it is obvious that several changes in arrangement and structure may be resorted to without deviating from the true spirit and scope of our invention.

What we claim is:

1. In apparatus for treating liquids by means of ultra-violet rays the combination of a plurality of tubular windows or chambers permeable to ultra-violet rays, manifolds connecting said tubular windows, and a lamp capable of emitting ultra-violet rays located in proximity to said tubular windows.

2. In apparatus for treating liquids by means of ultra-violet rays, the combination of a plurality of tubular windows or chambers permeable to ultra-violet rays, manifolds connecting said tubular windows, a lamp capable of emitting ultra-violet rays located in proximity to said tubular windows, and a reflector arranged over said lamp.

3. In apparatus for treating liquids by means of ultra-violet rays the combination of a plurality of parallel tubular windows or chambers permeable to ultra-violet rays, manifolds connecting said tubular windows, and a lamp capable of emitting ultra-violet rays located in proximity to said tubular windows.

4. In apparatus for treating liquids by means of ultra-violet rays, the combination of a plurality of parallel tubular windows or chambers permeable to ultra-violet rays, manifolds connecting said tubular windows, a lamp capable of emitting ultra-violet rays located in proximity to said tubular windows, and a reflector arranged over said lamp.

5. In an apparatus for treating liquids by means of ultra-violet rays, the combination with a plurality of chambers through which the liquid to be sterilized is caused to flow seriatim, each of said chambers provided

with a wall which is wholly permeable or transparent to the rays or permeable or transparent on the side of said chambers which is located in the direct path of said rays, and a lamp capable of emitting ultra-violet rays located in proximity to said windows.

6. In an apparatus for treating liquid by means of ultra-violet rays the combination of a plurality of chambers through which the liquid to be sterilized is adapted to flow seriatim, each of said chambers provided with a wall which is permeable to the rays, and a lamp capable of emitting ultra-violet rays located in proximity to said windows.

7. In an apparatus for treating liquids by means of ultra-violet rays the combination of a plurality of chambers through which the liquid to be sterilized is adapted to flow seriatim, each of said chambers presenting a face or side which is permeable to the ultra-violet rays, and a lamp capable of emitting ultra-violet rays located in proximity to said faces or sides.

8. In an apparatus for sterilizing liquids by means of ultra-violet rays comprising a passage through which the liquid to be sterilized is caused to flow, a source of ultra-violet rays located in close proximity to said passage, in combination with a baffle for imparting a swirling motion to said liquid.

9. In an apparatus for treating liquids by means of ultra-violet rays the combination of a passage through which the liquid is caused to flow, a source of ultra-violet rays supported adjacent said passage, and a baffle plate in said passage provided with one or more outstanding lip portions so that the liquid, impinging thereon, will take up a rotary or swirling movement in passing said source of rays.

In testimony whereof we have hereunto subscribed our names as follows: by the said VICTOR HENRI on the 28th day of February, 1918; by the said ANDRÉ HELBRONNER on the 28th day of February, 1918; and by the said MAX VON RECKLINGHAUSEN on the 19th day of March, 1918.

ANDRÉ HELBRONNER.
VICTOR HENRI.

By ANDRÉ HELBRONNER.
MAX VON RECKLINGHAUSEN.

Certificate of Correction.

It is hereby certified that Letters Patent No. 1,473,095, granted November 6, 1923, upon the application of Victor Henri, of Zurich, Switzerland, André Helbronner, of Paris, France, and Max von Recklinghausen, of New York, N. Y., for an improvement in "Apparatus for Sterilizing Liquids by Means of Ultra-Violet Rays," were erroneously issued to the inventors, whereas said Letters Patent should have been issued to *The R. U. V. Company, Inc., a Corporation of New York*, said corporation being assignee of the entire interest in said invention, as shown by the records of assignments in this office; and that the said Letters Patent should be read with this correction therein that the same may conform to the record of the case in the Patent Office.

Signed and sealed this 12th day of February, A. D., 1924.

[SEAL.]

KARL FENNING,
Acting Commissioner of Patents.
